ASTHMATIC'S WHEEL CHAIR

Janetta C. Crockett, Los Angeles, Calif.

Application July 22, 1957, Serial No. 47,026

Term of patent 14 years

(Cl. D15—1)

FIG.1.

FIG.2.

FIG.3.

FIG. 4.

FIG. 5.

FIG. 6.

Fig. 1 is a right side elevational view of an asthmatic's wheel chair showing my new design with the arm rest forward with the seat and the bed pan which are shown extended in Figs. 5 and 6, in retracted position;

Fig. 2 is a front elevational view of my new design with the arm rest inward;

Fig. 3 is a left side elevational view of my new design with the arm rest in the position shown in Fig. 2 with the seat and the bed pan which are shown extended in Figs. 5 and 6, in retracted position;

Fig. 4 is a perspective view of my new design with the arm rest in its lowermost inwardly directed position, the cabinet open and the tray extended upwardly therefrom, and the spittle cup forwardly positioned with the seat and the bed pan which are shown extended in Figs. 5 and 6, in retracted position;

Fig. 5 is another perspective view of my new design with the arm rest in the same position as shown in Fig. 4 but with the tray retracted, the cabinet closed, the

spittle cup rearwardly retracted, and the seat back rearwardly inclined, and the seat and bed pan both rearwardly extended; and

Fig. 6 is another perspective view of my new design as seen from a position behind and below Fig. 5, except that the seat back is in the upright position shown in Figs. 1-4.

I claim:

The ornamental design for an asthmatic's wheel chair, substantially as shown and described.
